UNITED STATES PATENT OFFICE.

EDWARD J. DOBBINS, OF NESHIAMINY, PENNSYLVANIA, ASSIGNOR TO THE AMERICAN PRISMATIC LIGHT COMPANY, OF PHILADELPHIA, PENNSYLVANIA.

DESIGN FOR A PRISM-PLATE.

SPECIFICATION forming part of Design No. 32,673, dated May 15, 1900.

Application filed April 11, 1900. Serial No. 12,487. Term of patent 7 years.

To all whom it may concern:

Be it known that I, EDWARD J. DOBBINS, a citizen of the United States, residing at Neshaminy, Bucks county, Pennsylvania, have 5 invented and produced a new and original Design for Prism-Plates, of which the following is a specification.

Figure 1 is a plan view of a prism plate, embodying my new design.

10 Figure 2 is a sectional elevation of said plate on the line 2—2 of Figure 1.

Figure 3 is a sectional elevation of said plate on the line 3—3 of Figure 1.

15 As shown in the drawings, the leading or material feature of my design consists in a series of convex projections, *a*, disposed or arranged upon the side of a plate *b*.

Each convex projection in form resembles

the segment of an ovoid, the plane face of which segment has been projected in parallelism with the major axis of such ovoid; each is, however, as to one end quite rotund, and, as to the other, tapers to a blunt point. 20

Having thus described my invention, what I claim as new, and desire to secure by Letters 25 Patent, is—

The design for a prism plate, as herein shown and described.

In testimony that I claim the foregoing as my invention I have hereunto signed my name 30 this 31st day of March, A. D. 1900.

EDWARD J. DOBBINS.

In presence of—

G. A. SCHWAB,

F. NORMAN DIXON.
